UNITED STATES PATENT OFFICE.

WILLIAM EVENSEN, OF CHICAGO, ILLINOIS, ASSIGNOR TO THE GOSS PRINTING PRESS COMPANY, OF CHICAGO, ILLINOIS, A CORPORATION OF ILLINOIS.

PLATE-CLAMPING MECHANISM FOR PRINTING-PRESSES.

1,028,340.

Specification of Letters Patent.

Patented June 4, 1912.

Application filed May 13, 1911. Serial No. 626,984.

To all whom it may concern:

Be it known that I, WILLIAM EVENSEN, a citizen of the United States, residing at Chicago, in the county of Cook and State of Illinois, have invented certain new and useful Improvements in Plate-Clamping Mechanism for Printing-PresSES, of which the following is a specification, reference being had to the accompanying drawings.

10 This invention relates to plate clamping mechanism for printing presses, on the cylinder of which two curved stereotype plates are adapted to be clamped abreast by a single operation.

15 Ordinarily in a two-plate wide press, the plates at each side of the press are adapted to be clamped on the cylinder independently of each other, but in four-plate wide presses it is customary to clamp the inner plates 20 and the end plates at each side of the press by a single operation, the inner plates being held in position by means of pressure transmitted through the medium of the end plates.

25 It is the object of this invention to provide a new and improved construction in which a plate may either be clamped on a press through the medium of the plate abreast of it on the press or be clamped in position independently of any other plate or plates, so that either two plates can be used for printing at a time or if desired a single plate only can be clamped in position.

30 It is another object of this invention to improve plate clamping mechanism of this type in sundry details hereinafter pointed out. The means by which I have accomplished these objects as applied to a cylinder press are illustrated in the drawings and 40 are hereinafter specifically described.

That which I believe to be new is set forth in the claims.

In the drawings,—Figure 1 is a side view of a portion of a cylinder of a four-plate 45 wide press embodying my improvements. Fig. 2 is a cross-section taken on line 2—2 of Fig. 1 with the cylinder given a partial rotation. Fig. 3 is an enlarged cross-section taken on line 3—3 of Fig. 2. Fig. 4 is an 50 enlarged detail, being a cross-section taken on line 4—4 of Fig. 3.

Referring to the several figures of the drawings,—10 indicates a shaft mounted in any suitable bearings not shown and adapted to be rotated by any appropriate means.

11—12 indicate the parts of a divided hub suitably mounted on the shaft 10 so as to rotate therewith.

13—14 indicate the parts of a cylindrical shell mounted on the hub 11—12 by means 60 of spokes 15.

16 indicates a ring mounted on the cylinder at its central point, said ring extending slightly beyond the periphery of the shell, its edges being beveled, as shown in 65 dotted lines in Fig. 1, to hold the beveled edge of a stereotype plate in position on the cylinder.

17 indicates slide-blocks mounted in grooves 18 in the shell 13—14 midway between the ring 16 and the end of the cylinder, each of which slide-blocks is provided with a head 19 adapted to slide upon the surface of the shell, its edges being beveled in order to properly engage the beveled 75 edge of a stereotype plate.

20 indicates slide-blocks slidably mounted in grooves 21 in the shell at its outer end, each of which slide-blocks 20 is provided with a head 22 adapted to slide upon the 80 surface of the shell, the inner edges of which heads are beveled in order to properly engage the beveled edge of a stereotype plate.

23 indicates two heavy semi-annular plates slidably mounted upon the hub members 11 and 12, respectively.

24 indicates pins mounted in the plates 23 and having a sliding fit in suitable openings in shell 13—14, said pins serving to cause the plates 23 to rotate with the shell 90 but at the same time permitting the said plates to slide freely longitudinally of the hub.

25 indicates a plurality of rods rotatably mounted in the plates 23. As shown in Fig. 95 3, each rod is provided with a flange 26 in a chamber 27 in the plate 23, between which flange 26 and a ring 28 carried by the plate is mounted a heavy coiled spring 29. Each of the rods 25 is screw-threaded 100 through one of the slide-blocks 20 and is provided upon its outer end with a suitable head 30 for the application of a wrench. 31 indicates rods screw-threaded into the inner ends of the rods 25, the direction and 105 the pitch of the threads being such that when the rod 25 is turned the rod 31 is forced inward just half as far as the slide-block 20 is moved by reason of the same turning of the rod 25. The rods 31 extend 110

through suitable openings in the shell and bear at their inner ends upon set-screws 32 in the outer faces of the slide-blocks 17.

33 indicates jam-nuts on the screws 32 by which the screws may be held in adjusted position.

34 indicates pins mounted in the shell 14 engaging grooves 35 in the rods 31 adapted to permit longitudinal movement of said 10 rods but to hold the rods against turning.

The rod 31 is of such a length and is so adjusted in the end of the rod 25 that the screw 32 may be adjusted to make the distance between the heads 22 and 19 of the 15 slide-blocks 20 and 17 very slightly shorter than the distance between the heads 19 and the ring 16 when the slide-blocks 17 are in contact with the ends of the rods 31. It will be understood that when this adjustment has once been made, the turning of the 20 rods 25 does not disturb this relative position, the head 22 always being forced twice as far to the right as is the head 19.

In use, when the width of plate to be used 25 has been determined upon, the rods 25 are turned to bring the heads 19 and 22 to the proper positions. When thereafter a plate 36 is placed in position upon one half of the cylinder with its inner edge engaged by the 30 ring 16 and with its outer edge a very short distance from the inner edges of the heads 19 of the slide-blocks 17, all that is necessary to do in order to clamp the plate firmly on the cylinder is to move the corresponding 35 plate 23 inward, moving inward with it of course the rods 31 and slide-blocks 17. The springs 29 thus hold the slide-blocks 17 yieldingly but firmly in contact with the plate regardless of any slight inaccuracies 40 in the trimming of the plate, the slideable clamping means 22 being spaced from the slideable clamping means 19 by the rods 25-31. If it were then desired to clamp another plate abreast of the plate 36 and of the 45 same width, this would be accomplished by turning the heads 30 of the rods 25 to move the clamps 22 to the left a short distance, serving to increase the distance between the clamps 22 and 19 sufficiently to permit of the 50 insertion of said plate, this movement having the effect of drawing the ends of the rods 31 from the heads of the screws 32, as will be readily understood. Under these conditions, when the plate 23 is moved inward 55 and locked in position in the usual manner, the outer stereotype plate serves to hold the clamps 19 in contact with the plate 36, and the springs 29 serve to hold the rods 25 and the clamps 22 carried thereby yield- 60 ingly but firmly in contact with the outer edge of the outer plate, thus locking the two stereotype plates properly in position abreast regardless of any slight inaccuracies in the trimming of the plates.

65 I prefer to move the plates 23 inward and

to lock them in position by the means shown and described in Letters Patent No. 988,559, granted to me on April 4, 1911, the pin 37 of such a mechanism being shown in my drawings, said pin 37 corresponding to the 70 pin 17 of my said patent. Thus by the turning of the pin 37 the plate 23 is moved to the right and automatically locked in position.

While I have described my invention in 75 connection with a cylinder press, I do not desire to limit myself to its use in such a press, since it may easily be applied also to other forms of presses. The claims are therefore not to be construed to be limited 80 to a cylinder press except as hereinafter specifically limited thereto.

While I have shown and described means for locking two plates abreast on a press by a single operation, the outer plate serving 85 to hold the clamps in contact with the inner plate, together with means for locking only one of such two plates without regard to the other plate, I do not wish to limit myself to the application of this invention to two 90 plates abreast, as the invention might manifestly be applied to a greater number of plates abreast, the means by which the slideable clamps are moved inward toward the stationary clamps being such that the distance between the stationary clamps and the innermost set of slideable clamps may be kept approximately equal to the distance between each set of slideable clamps and the set of slideable clamps next adjacent to it. 100

It is seen that when two plates are clamped abreast on the cylinder 14 the plates themselves serve to space apart the clamping means and the rods 25-31 do not so serve for the reason as explained above that the effective length of said rods is slightly less than the width of the outside plate, but when only one plate 36 is to be clamped on the cylinder the rods 25-31 serve as additional or alternative means in lieu of the outside plate for 110 spacing one set of slideable clamping means away from the other set of slideable clamping means.

I have provided a construction by which either one plate alone or two plates abreast 115 may be locked upon a press, the locking in either case being effected by the movement inward of the plate 23, it requiring no more time or work to lock two plates than it does to lock one plate. At all times when the locking means are adjusted exactly for a single plate, such locking means are also approximately in adjustment for locking two plates abreast. 120

What I claim as my invention and desire 125 to secure by Letters Patent is,—

1. The combination with a plate-support, means carried by said plate-support adapted to engage and hold in position the inner edge of a stereotype plate, slideable clamp- 130

ing means adapted to engage the outer edge of said plate and the inner edge of a second plate, slideable clamping means adapted to engage the outer edge of said second plate, 5 and means for moving said last-named slideable clamping means inward whereby said plates are clamped in position, said second plate serving to space said last-named slideable clamping means away from said first-named slideable clamping means, of alternative means in lieu of said second plate for spacing said first-named slideable clamping means a distance away from said second-named slideable clamping means whereby by 10 the movement of said second-named slideable clamping means inward said first-named plate may be clamped in position independently of said second-named plate.

2. The combination with a plate-support, 20 means carried by said plate-support adapted to engage and hold in position the inner edge of a stereotype plate, slideable clamping means adapted to engage the outer edge of said plate and the inner edge of a second plate, slideable clamping means adapted to engage the outer edge of said second plate, and means for moving said last-named slideable clamping means inward whereby said plates are clamped in position, said second 25 plate serving to space said last-named slideable clamping means away from said first-named slideable clamping means, of alternative means in lieu of said second plate for spacing said first-named slideable clamping means away from said second-named slideable clamping means by a distance approximately equal to the distance which said first-named slideable clamping means is permitted to move away from said first-named 30 clamping means.

3. The combination with a plate-support, 35 clamping means carried by said plate-support adapted to engage and hold in position the inner edge of a stereotype plate, slideable clamping means adapted to engage and hold in position the outer edge of said plate and the inner edge of a second plate, slideable clamping means adapted to engage and hold in position the outer edge of said second plate, and means for moving said last-named slideable clamping means inward for clamping both of said plates in position, of adjustable means for forcing said slideable clamping means variable distances toward said first-named clamping means whereby the distance by which said first-named and said second-named slideable clamping means are forced to be separated is kept approximately equal to the distance to which said first-named clamping means and said first-named slideable clamping means are free to move from each other. 4. The combination with a plate-support, 45 clamping means carried by said plate-support adapted to engage and hold in position the inner edge of a stereotype plate, slideable clamping means adapted to engage the outer edge of said plate and the inner edge of a second plate, slideable clamping means adapted to engage the outer edge of said second plate, and means for moving said last-named slideable clamping means inward whereby said plates are clamped in position, said second plate serving to space said last-named slideable clamping means away from said first-named slideable clamping means, of a plurality of rods spacing said first-named slideable clamping means away from said second-named slideable clamping means.

5. The combination with a plate-support, 50 clamping means carried by said plate-support adapted to engage and hold in position the inner edge of a stereotype plate, slideable clamping means adapted to engage the outer edge of said plate and the inner edge of a second plate, slideable clamping means adapted to engage and hold in position the outer edge of said second plate, and a plurality of rods one 55 of which is screw-threaded through each of said last-named slideable clamping means, of a plurality of rods one of which is connected by a screw-threaded joint with each of said first-named rods, each of said last-named rods having a bearing against one of the first-named slideable clamping means, whereby by the turning of said first-named rods said slideable clamps are moved toward 60 said first-named clamping means, the screw-threads on said rods being such that said second-named slideable clamps are moved approximately twice as far as are said first-named slideable clamps.

6. The combination with a plate-support, 65 clamping means carried by said plate-support adapted to engage and hold in position the inner edge of a stereotype plate, slideable clamping means adapted to engage and hold in position the outer edge of said plate and the inner edge of a second plate, slideable clamping means adapted to engage and hold in position the outer edge of said second plate, and a plurality of rods each of which is screw-threaded through one of said last-named slideable clamping means, of a plurality of rods each of which is screw-threaded into the end of one of said first-named rods, the threads on the last-named rods being in 70 the same direction and of approximately half the pitch of those on the exterior of the first-named rods, said last-named rods being adapted to bear on said first-named slideable clamping means and being of such a length that when the first-named slideable clamping means are in contact with said last-named rods the distance between said first-named slideable clamping means and the second-named slideable clamping means is approximately 75 equal to the distance between said

first-named slideable clamping means and said first-named clamping means.

7. The combination with a plate-support, clamping means carried by said plate-support adapted to engage and hold in position the inner edge of a stereotype plate, slideable clamping means adapted to engage and hold in position the outer edge of said plate and the inner edge of a second plate, slideable clamping means adapted to engage and hold in position the outer edge of said second plate, a plurality of rods each of which is screw-threaded through one of said last-named slideable clamping means, and a plurality of springs each of which tends to hold one of said rods yieldingly against movement away from said first-named clamping means, of a plurality of rods one of which is connected by a screw-threaded joint with each of said first-named rods, each of said last-named rods having a bearing against one of the first-named slideable clamping means, whereby by the turning of said first-named rods said slideable clamps are moved toward said first-named clamping means, the screw-threads on said rods being such that said second-named slideable clamps are moved approximately twice as far as are said first-named slideable clamps.

15 8. The combination with a plate-support, clamping means carried by said plate-support adapted to engage and hold in position the inner edge of a stereotype plate, slideable clamping means adapted to engage and hold in position the outer edge of said second plate, a movable member adapted to be slid relative to said plate-support, a plurality of rods mounted in said movable member each of which rods is screw-threaded through one of said last-named slideable clamping means, and a plurality of springs each of which tends to hold one of said rods yieldingly

against movement relative to said movable support away from said first-named clamping means, of a plurality of rods one of which is connected by a screw-threaded joint with each of said first-named rods, each of said last-named rods having a bearing against one of the first-named slideable clamping means, whereby by the turning of said first-named rods said slideable clamps are moved toward said first-named clamping means, the screw-threads on said rods being such that said second-named slideable clamps are moved approximately twice as far as are said first-named slideable clamps.

9. The combination with a plate-support, clamping means carried by said plate-support, and two sets of slideable clamping means, between which clamping means two stereotype plates are adapted to be secured abreast on said plate-support, of means for adjusting both sets of slideable clamping means by a single operation toward said first-named clamping means, the outer clamping means being moved by this adjustment twice as far as the intermediate clamping means.

10. The combination with a plate-support, clamping means carried by said plate-support, and a plurality of sets of slideable clamping means, between which sets of clamping means a plurality of stereotype plates are adapted to be secured abreast on said plate-support, of means for moving said slideable clamps toward said first-mentioned clamps so that the distance between said first-mentioned clamps and the innermost set of slideable clamps may be kept approximately equal to the distance between each set of slideable clamps and the set next adjacent to it.

WILLIAM EVENSEN.
